US0D1010257S

(12) **United States Design Patent** (10) Patent No.: **US D1,010,257 S**
(45) Date of Patent: ** Jan. 2, 2024

(54) **ROBOT CLEANER**

(71) Applicant: **SUZHOU RADIANT
PHOTOVOLTAIC TECHNOLOGY
CO., LTD**, Suzhou (CN)

(72) Inventors: **Xiaofeng Xu**, Suzhou (CN); **Xianshan Qi**, Suzhou (CN); **Jianrong Xu**, Suzhou (CN); **Fei Xu**, Suzhou (CN)

(73) Assignee: **SUZHOU RADIANT
PHOTOVOLTAIC TECHNOLOGY
CO., LTD**, Suzhou (CN)

(**) Term: **15 Years**

(21) Appl. No.: **29/681,607**

(22) Filed: **Feb. 27, 2019**

(51) LOC (14) Cl. **15-05**

(52) U.S. Cl.

USPC **D32/21**

(58) **Field of Classification Search**

(57) **CLAIM**

The ornamental design for a robot cleaner, as shown and described.

DESCRIPTION

FIG. 1 is a top perspective view of the robot cleaner showing the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines show portions of the robot cleaner that form no part of the claimed design.

1 Claim, 7 Drawing Sheets
